UNITED STATES PATENT OFFICE.

ALEXANDER FOX, OF GALESBURG, ILLINOIS.

CAR-COUPING.

SPECIFICATION forming part of Letters Patent No. 412,380, dated October 8, 1889.

Application filed July 5, 1889. Serial No. 316,489. (No model.)

To all whom it may concern:

Be it known that I, ALEXANDER FOX, a citizen of the United States, residing at Galesburg, in the county of Knox and State of Illinois, have invented certain new and useful Improvements in Car-Couplings, of which the following is a specification.

This invention relates to improvements in car-couplings; and it consists in constructions and combinations hereinafter described and claimed.

In the accompanying drawings, which illustrate my invention, Figure 1 is an end elevation of the body of an ordinary freight-car, partly broken away, and an elevation of my invention as applied thereto; Fig. 2, a top plan of the draw-head; Fig. 3, a sectional plan of the draw-head and coupling-pin and plan of the coupling-link as engaged with the coupling-pin; Fig. 4, a sectional elevation of the draw-head and coupling pin and link; Fig. 5, a sectional elevation of the draw-head, coupling pin and link, draw-bar, and the coupling-pin-lifting mechanism; Fig. 6, a detail, a sectional elevation in the line 6 6 in Fig. 5; and Fig. 7, a perspective of the coupling-pin.

The same reference-letter hereinafter used indicates the same part of the coupling where used in the different figures of the drawings.

The car A (partly shown in the drawings) is an ordinary car. The draw-bar B is also of ordinary construction, attached to the car as shown; or it may be attached in any ordinary manner. The draw-head D has an opening or throat d for the reception of the link, which opening does not differ in any substantial degree from the ordinary opening for the same purpose. The draw-head has a slot d' in its upper wall or part and two holes d² d³ in its lower wall or part, for the reception of the coupling-pin E, as hereinafter described. The rear side of the slot d' and the rear side of the rear hole d³ are in line, as are the front side of the slot and the front side of the hole d².

The coupling-pin E is formed of a longer arm e and a shorter arm e', connected by a bar e²; or, in other words, is formed of a U-shaped bar, with a short arm and a long arm, united, preferably, at right angles to the bar which connects them. The long arm e of the

coupling-pin has a slot e³ extending lengthwise of itself, in which is located a swinging trigger or catch G, having a shoulder g on its front side, below which a tail-piece g' extends downwardly and somewhat rearwardly. The trigger G has an oblique slot g² in its upper end, which extends from a higher point near the front side of the catch to a lower point toward its rear side, through which slot a pin g³ passes to pivot the trigger to and in the arm e of the coupling-pin.

H is an ordinary coupling-link.

The pin E is seated, with both of its arms e e', in the slot d' of the draw-head, with its arm e in the hole d³ and its arm e' in the hole d². When the coupling-pin is in its lower position, as shown at Fig. 4, the catch G will hang on the pin g³, which will be in the higher and forward end of the slot g². When the coupling-pin is raised to the position shown at Fig. 5, the catch G, by reason of its heavier portion in rear of the pin g³, will swing forward at its lower end until stopped by its tail-piece g' striking the side wall of the hole d³, thus bringing the shoulder g over the bottom d⁴ of the draw-head and holding the catch G to support the coupling-pin in its elevated position, as shown at same figure.

I is a rod or bar, with its forward end in the slot e³, where it is pivoted at i near the lower end of the arm e of the coupling-pin. The rear part of the rod I passes through a tubular carrier I', which has lateral journals or trunnions i', which have bearings in the sides of a pendant J, through which the carrier I' passes, as shown at Figs. 5 and 6. The carrier I' can swing on its bearings i' to permit of raising and lowering the forward end of the rod I and with it the coupling-pin, and the rod I can move endwise in the tube I', as may be required in the various movements of said rod I. The tubular carrier I' is so mounted in the pendant J that its forward end cannot fall to the ground if the rod I becomes disengaged therefrom, and the rod I is so short that it cannot fall to the ground if released at its rear end.

K is a lifting-bar located transversely of the car and with its mid-length part beneath the forward part of the rod I, as shown at Figs. 1 and 5. From each end of the lifting-bar K

a chain L extends upwardly through suitable guide-eyes a a' to the top of the car, where it terminates with a hand-hold l. A headed pin a² projects from the car through 5 a long link l' of the chain L. The upper ends of the long links l', resting on the pins a², will sustain the lifting-bar K in its lower position. (Indicated by dotted lines at Fig. 1 and shown by full lines at Fig. 5.) Either link l', sliding on 10 its pin a², will permit raising one end of the lifting-rod K by means of the hand-hold l into the position shown by full lines at Fig. 1, and it will be evident that either end of the bar K may be raised by taking hold thereof when 15 its supporting-chain will bend out of line to permit the same.

The normal position of the lifting-bar K is the horizontal position shown by dotted lines at Fig. 1, and when either of its ends is temporarily 20 lifted by either means hereinbefore described, and into the position shown by the full lines at same figure, the bar K will come in contact with the rod I and lift the coupling-pin to the position shown at Fig. 5, when 25 the trigger or catch G will swing forward at its lower end and its shoulder g, engaging with the bottom of the draw-head, will sustain the coupling-pin in its elevated position, as shown at same figure. When the trigger or catch 30 G sustains the weight of the coupling-pin, as last described, the pin g³ will rest in the lower and rear end of the slot g².

In coupling, the link H, carried by an approaching draw-head, enters the throat d and 35 striking the catch G, as shown at Fig. 5, knocks it back and out of engagement with the bottom of the draw-head, and the coupling-pin being thus liberated drops into the position shown at Fig. 4, with its arm e' through 40 the link H to effect a coupling. Raising one end of the lifting-bar K, as hereinbefore described, will uncouple the cars, and the catch G, operating as described, will again sustain the coupling-pin in place for another automatic 45 coupling. In its elevated position, as shown at Fig. 5, both limbs e and e' of the coupling-pin rest in the slot d', which serves as a guide in the descending movement of the coupling-pin. The inclined slot g² allowing 50 the trigger or catch G to move forward at its upper end while supporting the coupling-pin, will insure a more certain release of the shoulder g from the bottom of the draw-head should the link H incline upwardly at its entering 55 end, and thus strike the catch G at a higher point. In such case the shoulder g will be released before the point where the catch is struck by the link has passed into the arm e of the coupling-pin, as will be seen from the 60 dotted-line representation of the catch G at said figure. An ordinary pivot for the catch G would operate; and I do not limit my main claims for this trigger or catch to the slot-pivot.

65 At Fig. 4 the parts are shown in positions immediately after the coupling-pin drops, and

at Fig. 3 the relative positions of the parts are those after the link H is drawn, as when pulling a car.

In coupling, if the link is in the position 70 shown at Fig. 4, when the coupling-pin is raised the shoulder g on the trigger or catch G will rest on the top of the link, as shown by dotted lines at same figure, and sustain the coupling-pin until the engine starts the 75 car or it is otherwise started to withdraw the link, when the coupling-pin will drop and the shoulder g engage with the bottom of the draw-head and sustain the coupling-pin for coupling, as hereinbefore described. 80

It will be seen that all of the operations in coupling and uncoupling can be effected with my device without the operator going between the cars, and should the catch G become deranged or inoperative from any cause, or 85 should it be desirable from any other cause to hold and retain the coupling-pin in a higher and uncoupled position, as is sometimes necessary, this can be done by lifting either end of the lifting-bar K and engaging it with the 90 adjacent hook m, which extends down from the car, as shown by broken lines at Fig. 1.

The short limb e' of the coupling-pin, connected as it is to the limb e, is very strong, and, seated as it is, not liable to be damaged. 95 An ordinary coupling-pin can be used in the slot d' and the hole d².

Having thus described my invention, what I claim as new, and desire to secure by Letters Patent, is--

1. In a car-coupling, the combination of a draw-head, a coupling-pin having a shorter limb to engage with the coupling-link and a longer limb provided with a pin g³, and a trigger having a shoulder g engaging with the draw-head and a slot g² engaging with pin g³, substantially as described. 100

2. In a car-coupling, the combination of a draw-head, a coupling-pin having a shorter limb to engage with the coupling-link, and a longer limb provided with a pin g³, and a trigger having a shoulder g engaging with the draw-head, a slot g² engaging with pin g³, and the tail-piece or stop g', substantially as described. 110

3. In a car-coupling, the combination of a draw-head, a coupling-pin having a shorter limb to engage with the coupling-link and a longer limb provided with a pin g³, a trigger having a shoulder g engaging with the draw-head and a slot g² engaging with pin g³, and a lifting-bar extending across the car and adapted to raise the coupling-pin, substantially as described. 120

4. In a car-coupling, in combination with a draw-head and a vertically-sliding coupling-pin having limbs e e' and a swinging catch or trigger hinged thereto, a rod I, hinged beneath the car, and a rod transversely of the car and carried by suspending-chains, substantially as and for the purpose specified. 125

5. In a car-coupling, in combination with a

draw-head and a vertically-sliding coupling-pin having limbs $e\ e'$ and a swinging catch or trigger hinged thereto, a rod I , hinged to the coupling-pin, a hinged rod I' , in which it slides endwise, and a lifting-bar extending across the car, substantially as and for the purpose specified.

In testimony whereof I affix my signature in presence of two witnesses.

ALEXANDER FOX.
